UNITED STATES PATENT OFFICE.

EMMETT McCONVILLE, OF PITTSBURG, PENNSYLVANIA.

STEAM-ENGINE.

SPECIFICATION forming part of Letters Patent No. 628,953, dated July 18, 1899.

Application filed December 1, 1898. Serial No. 697,983. (No model.)

To all whom it may concern:

Be it known that I, EMMETT McCONVILLE, a citizen of the United States, residing at Pittsburgh, in the county of Allegheny and State of Pennsylvania, have invented certain new and useful Improvements in Steam-Engines; and I do hereby declare the following to be a full, clear, and exact description of the invention, such as will enable others skilled in the art to 5 which it appertains to make and use the same.

My invention has reference to improvements in steam-engines whereby much saving of steam and increased horse-power are gained, and which consists of certain novel 15 features of construction, which will be hereinafter fully described in the specification and pointed out in the claims.

The object of my invention is to so construct a steam-engine that a reciprocating cylinder 20 which moves in an opposite direction to the within-contained piston upon ways or guides will have the friction upon said moving cylinder reduced to a minimum through the medium of friction-rollers properly arranged between the moving cylinder and its supporting 25 guides.

A further object of my invention is to so construct the connecting-rod with springs or any other yielding devices that all undue 30 shocks will be eliminated from the wrist-pin when the engine is changing its position from forward to backward stroke or the opposite.

A further object of my invention is to connect a rocking lever upon a moving cross-head, 35 with its opposite ends attached, respectively, to an eccentric-rod and a valve-rod.

A further object of my invention is to provide a pair of cross-heads, one connected direct to a piston and connecting rod and having 40 openings for allowing reach-bars for connecting to the cylinder-head, the opposite ends being secured to a yoke cross-head adjacent to two connecting-rods.

A further object of my invention is to provide parallel jointed steam connections whereby a movable cylinder can reciprocate and allow said jointed rods to accommodate themselves to the moving cylinder.

It is obvious to those conversant with steam- 45 engines that this class has advantages not possessed by stationary cylinder-engines.

The cylinder moving opposite to the piston

shortens the stroke one-half, and consequently can move with double the velocity in completing a stroke, thus increasing the 55 horse-power one hundred per cent. minus friction of the moving parts.

In the drawings, Figure 1 is a side elevation of my improved engine. Fig. 2 is a plan of the same. Fig. 3 is a plan in detail of the 60 cross-heads and cylinder-heads, parts being broken away and partly in section, exhibiting the construction and relative position of the three connecting-rods. Fig. 4 is a front elevation of the yoke cross-head with the 65 valve-rod lever pivoted thereon and the reach-bars and connecting-rods secured thereto. Fig. 5 is a front elevation of the piston-rod cross-head. Fig. 6 is a transverse vertical section of the steam-cylinder and valve-chamber secured to its accompanying guides or ways by friction-rollers. Fig. 7 is a detail, partly in section, of a connecting-rod head, exhibiting the means for arranging the spring devices. Fig. 8 is a detail in section of the 75 relative position the guides or ways assume toward the cylinder, with the friction-rollers removed to exhibit more fully the bearing-surfaces for the friction-rolls. Fig. 9 is a modification of the friction-rolls and their 80 bearings in the guides and cylinder.

The engine consists of a bed A, having ordinary boxes for a shaft B and which are integral with three cranks—viz., two side cranks b b and a central crank b'. The side cranks 85 b carry connecting-rods C C. The opposite ends of said connecting-rods C are secured to a yoke cross-head D by means of pivotal pins d d, respectively. Also secured to said yoke cross-head D by pins d are reach-bars E E, 90 their opposite ends being secured by pins e e through ears f f, the latter being integral with the front cylinder-head F of the steam-cylinder F'. The central crank b', previously referred to, carries a much heavier connecting-rod C' and which is secured at its opposite end to a cross-head G. Said cross-head supports the piston-rod H, which makes direct connection with the steam-cylinder through the medium of a piston. Cross-head G has 95 two rectangular openings g g for allowing the reach-bars E to pass through freely, but not contacting said openings g.

The main connecting-rod C', previously re-

ferred to, not only receives all the load that comes upon its crank, but it also must operate the side cranks *b* for moving the reciprocating cylinder *F'*, and to provide for sudden shocks outside of cushioning by the steam, which may or may not operate, I provide an effective means through the medium of two opposing springs *I*, (see Fig. 7,) which will be hereinafter more fully set forth.

- 10 Secured to the yoke cross-head by means of a wrist-pin *k* is a lever *K*, fulcrumed near its lower end and adapted to connect with an eccentric-rod *L* at its lower end and at its upper end to a valve-rod *M*.
- 15 Secured to the bed *A* by bolts *a* are ways or guides *N*, having an external **V**-shaped contour *n* for the reception of friction-rollers *P*. The ways *F²* upon the cylinder *F'* are internally **V**-shaped in their contour and make connection with ways *N* through the medium of friction-rollers *P*, previously referred to. (See Fig. 6.) To prevent any slight movement of the steam-cylinder and to keep it in alinement, I provide an annular rib *p* centrally located on each friction-roller, and I also provide longitudinal grooves *j²* in the **V**-bearings *n* and *F²*, respectively, for said ribs to move in. By this means the cylinder is in perfect alinement both laterally and vertically.
- 20 The friction-rollers *P* are provided with oil-holes *p'* and also covers *q*, the latter for preventing dust from entering among the rollers.
- 25 The springs *I*, previously referred to, play against the opposite ends of a bisected box *R*. Said box is secured in the head of the connecting-rod by side flanges *r*. (Shown in dotted lines in Fig. 7.) Boxes *R* are recessed for holding said springs. Projections *s* extend partly into said recesses to more fully operate as bearing-surfaces for springs *I* to rest against.
- 30 Fig. 9 is a modification of the friction-roll-

ers, which are well adapted for heavy reciprocating cylinders. The reciprocating cylinder is connected to jointed steam connections *t*, which oscillate in harmony with the reciprocating steam-cylinder and furnish steam and exhaust similar to a stationary cylinder.

Having described my invention, that which I desire to secure by Letters Patent of the United States is—

1. In combination with a reciprocating steam-cylinder moving on ways or guides, friction-rollers interposed between said cylinder and guides, longitudinal grooves in projections integral with said cylinder, also similar grooves in the ways or guides secured to the engine-bed, said guides being adapted to receive friction-rolls which are provided with annular ribs for entering said longitudinal grooves in the cylinder and ways, for the purpose as shown and described.
2. In combination with a reciprocating engine mounted on ways secured to an engine-bed and operated by two reach-rods and three connecting-rods and two cross-heads, of an eccentric and valve rod connection through the medium of a lever pivoted to a movable yoke cross-head, as specified.
3. In combination with a steam-engine, a connecting-rod provided with a bisected box, and an enlarged head surrounding said box, springs at opposite ends or sides of said box located in recesses formed in the same, and projections integral with the connecting-rod and extending into said recesses against said springs, substantially as described.

In testimony whereof I affix my signature in presence of two witnesses.

EMMETT McCONVILLE.
